The ornamental design for a luminaire, as shown and described.

DESCRIPTION

FIG. 1 is a front perspective view of a luminaire showing our new design;

FIG. 2 is a rear perspective view thereof;

FIG. 3 is a front elevational view thereof;

FIG. 4 is a right side elevational view thereof, the left side being a mirror image;

FIG. 5 is a rear elevational view thereof;

FIG. 6 is a top plan view thereof; and,

FIG. 7 is a bottom plan view thereof.

The inner rectangular area at the front of the luminaire shown in FIGS. 1 and 3 represents a light emitting surface of an area light source, such as an OLED panel.

The inner broken line rectangles shown in FIGS. 2 and 5 represent a light emitting surface of an area light source, such as an OLED panel, and a mounting ring plate therefor.

The broken lines shown in FIGS. 1, 2 and 5 represent an extension of the pendent arm for attaching the luminaire to a wall or other vertical attachment surface. The additional broken lines at the opposite end of the pendent arm shown in FIG. 1 represent an attachment surface cover plate. The structures shown in broken lines form no part of the claimed design.
